UNITED STATES PATENT OFFICE.

BENJAMIN E. D. STAFFORD AND ETHAN I. DODDS, OF PITTSBURGH, PENNSYLVANIA,
ASSIGNORS TO FLANNERY BOLT COMPANY, OF PITTSBURGH, PENNSYLVANIA.

STAY-BOLT STRUCTURE.

1,201,887.

Specification of Letters Patent. Patented Oct. 17, 1916.

Application filed February 29, 1916. Serial No. 81,259.

To all whom it may concern:

Be it known that we, BENJAMIN E. D. STAFFORD and ETHAN I. DODDS, citizens of the United States, and residents of Pittsburgh, in the county of Allegheny and State of Pennsylvania, have invented certain new and useful Improvements in Stay-Bolt Structures; and we do hereby declare the following to be a full, clear, and exact description of the invention, such as will enable others skilled in the art to which it appertains to make and use the same.

This invention relates to improvements in stay bolt structures, an object of the invention being to provide simple and efficient means for connecting a rigid stay bolt with an outer boiler sheet in such manner that it will be permitted to yield in all directions without subjecting either of the boiler sheets to undue strain, to accommodate movement of said sheets (especially the inner sheet) due to expansion and contraction.

With this and other objects in view, the invention consists in certain novel features 25 of construction and combinations of parts as hereinafter set forth and pointed out in the claims.

The accompanying drawing is a view partly in section and partly in elevation 30 illustrating our invention.

1 represents an inner boiler sheet and 2 the outer sheet,—the latter being provided with a bolt hole 3, a portion of the wall of which is curved to form a seat 4. A stay bolt 5 is secured to the inner sheet 1 and passes through the hole 3 in the outer sheet,—the projecting portion of said bolt being screw threaded as shown at 6. The bolt is made with a tell-tale hole 7 in its 40 outer portion and this hole is open at the upset end 8 of the bolt.

A gland or yielding member 9 is made with an internally threaded portion 10 to receive the threaded outer portion of the stay bolt, and the said portion 10 of the gland projects into the hole in the boiler sheet 2 and is formed near its inner end with a curved face 11 disposed parallel with and adapted, under normal working conditions of the boiler, to engage the curved seat in said boiler sheet. The gland 9 also comprises a bowed flange 12 which lends flexibility to the whole structure, and this bowed flange is made at its free edge with

enlarged portion forming a base 13 seated 55 against the outer boiler sheet 2 and welded thereto as indicated at 14.

Our improvements provide simple means which will afford such a yielding connection for the stay bolt to the boiler sheet as 60 will permit universal movement of the outer end of the bolt and allow the same to so yield longitudinally as to insure free movement of the inner sheet and relieve the bolt of the greater portion of strain or fatigue 65 such as usually borne by rigid stay bolts.

At certain times, as when the boiler is cold, there will be a gap or clearance space 15 between the curved face 11 of the gland and the curved seat 4 in the outer boiler 70 plate. When the boiler is under pressure, the gap or clearance space 15 will be closed; with the curved face 11 of the gland in contact with the curved seat 4,—bringing the bolt under tension between the boiler sheets. 75 The gland will thus be relieved of any high pressures.

Our improvements serve not only to afford a flexible and universal coupling means for the bolt to the boiler sheet, but they also 80 prevent leakage. The chamber 17 formed in the gland may contain stiff grease or other lubricant which serve to protect the device against collection of incrustation.

Having fully described our invention what 85 we claim as new and desire to secure by Letters-Patent, is:—

1. In a stay bolt structure, a yielding member comprising a central threaded part to receive the outer threaded end of a stay 90 bolt, said yielding member also having a base member to lie flat against the outer face of the outer boiler sheet and adapted to be secured to the same.

2. In a stay bolt structure, a yielding 95 member comprising a central threaded part to receive the outer threaded portion of a stay bolt and also having a bowed flange provided with a base portion adapted to be welded to the outer face of an outer boiler 100 sheet.

3. In a stay bolt structure, the combination with an outer boiler sheet having a bolt hole forming a seat, and a stay bolt having a threaded outer end portion, of a yielding 105 member having a threaded central portion to receive the threaded portion of the bolt, said central portion also having a curved

face near its inner end disposed substantially parallel with the curved seat in the boiler sheet, and said yielding member also formed with a bowed portion having a base 5 portion lying flat against the outer face of the outer boiler sheet and welded thereto.

In testimony whereof, we have signed this

specification in the presence of two subscribing witnesses.

BENJAMIN E. D. STAFFORD.
ETHAN I. DODDS.
